PLOW STOCK

George L. Jones, Rienzi, Miss., assignor of one-half to W. H. Caver, Rienzi, Miss.

Application August 16, 1938, Serial No. 225,225

2 Claims. (Cl. 97—109)

This invention relates to new and useful improvements in plow stocks.

The principal object of the present invention is to provide a plow stock which will be adjustable 5 to permit various depths of plowing.

Another important object of the invention is to provide a plow stock which will permit repair or replacement of parts in an easy and convenient manner.

10 These and other important objects and advantages of the invention will become apparent to the reader of the following specification.

In the drawings:

Figure 1 represents a side elevational view.

15 Figure 2 is a top plan view.

Figure 3 is a bottom plan view.

Figure 4 is a plan view of the foot piece.

Figure 5 is a side elevational view of the frog member.

20 Figure 6 is an elevation of one section of the clamp.

Figure 7 is a side elevational view of the sword.

25 Referring to the drawings wherein like numerals designate like parts, it can be seen that numerals 5—5 represent a pair of plow beams which can be secured together at the portion 6.

A bolt 7 extends through the hump portion 8 of these beams and a spacer 9 is interposed between the beams at this point to properly space the 30 beams.

35 A pair of strap members or plates 10—10 have the sword member 11 interposed between the same and a rivet or bolt 12 extends through these plates 10 to properly secure the sword 11. A second rivet or bolt 13 is disposed through the plates 10—10 to assist in holding the plates in proper 40 connected relation. The bolt 13 extends through the arcuate slot 14 of the sword or blade 11 and obviously by loosening this bolt 13 the sword can 45 be properly adjusted and held in this adjusted position by tightening the member 13. The sword 11 is provided with the cutting edge 15 which is to depend below the lower edges of the plates 10. These plates 10 have a reduced forward portion 45 into which seats the lower rearwardly disposed toe portion 20 of the beams 5. The crotch portions 18 of the beams at these fingers 20 receive the beveled lower ends of the handle shanks 16, which are provided with the handles 17 at their 50 upper ends. A plate 19 is disposed adjacent the lower ends of the shanks 16, beams 5 and plates 10 and these latter elements are all secured to the said plate 19 by rivets or bolts 21 and 23. Furthermore, a frog 22 has its plate portion *a* 55 interposed between the lower portions of the

beams 5 and the forward end portions of the plates 10 and these latter portions are secured by rivets or bolts to the plate portion *a* of the frog 22, while the arm *b* of the frog protrudes forwardly and into the confines of the foot generally referred to by numeral 33 (see Figures 1 and 4), the latter consisting of an elongated metal strap bent to form the two side portions 35 and which at its intermediate portion is formed to provide the elongated loop 34 for receiving the said arm *b*, as well as the bolt 26a for the plow blade 26. The complete foot 33 has the loop 34 at one end while a handle 33a is provided at its opposite end to facilitate adjusting of the foot when adjustments are to be made with respect to the openings 27 and 28 and with the agency of the pin or bolt 29. A bolt 24 serves to secure the arm *b* of the frog 22 properly to the loop 34 of the foot 33.

Brace members 30 can extend from the aforementioned connecting bolt 7 to connect the handle shank by way of bolts 31.

The clamp means is denoted by numeral 37 and consists of a pair of angle members 38 each of which at one end is threaded as at 39 and its 25 opposite end formed with an eye 40. The threaded end at one section fits through the eye of the other section and nuts 41 are disposed on the threaded portions.

While the foregoing specification sets forth the 30 invention in specific terms, it is to be understood that numerous changes in the shape, size and materials may be resorted to without departing from the spirit and scope of the invention as claimed hereinafter.

Having described the invention what is claimed as new is:

1. In a plow, a pair of beam bars having downwardly disposed tail portions, hand bars having tapered lower ends, said tail portions provided with rearwardly disposed finger members defining crotches in which the tapered lower ends of the bars are disposed, and a plate interposed between the lower ends of the tail portions and between the lower ends of the hand bars and securing means between the said plate and the beams and between the plate and the lower ends of the hand bars, a plow, an adjustable shoe carrying the plow, an arm having one end secured between the lower ends of the said tail portions and its 50 opposite end secured to the said shoe.

2. In a plow, a pair of beam bars having downwardly disposed tail portions, hand bars having tapered lower ends, said tail portions provided with rearwardly disposed finger members defin- 55

ing crotches in which the tapered lower ends of the bars are disposed, and a plate interposed between the lower ends of the tail portions and between the lower ends of the hand bars and securing means between the said plate and the beams and between the plate and the lower ends of the hand bars, a plow, an adjustable shoe carrying

the plow, an arm having one end secured between the lower ends of the said tail portions and its opposite end secured to the said shoe, said shoe being adjustably connected to the beams and having a handle at its upper end.
